UNITED STATES PATENT OFFICE

CLARENCE W. MOORE, OF ROSLYN, PENNSYLVANIA, ASSIGNOR TO RITTER DENTAL MANUFACTURING COMPANY, INC., OF ROCHESTER, NEW YORK, A CORPORATION OF DELAWARE

FOUNTAIN CUSPIDOR

Original application filed November 30, 1926, Serial No. 151,736. Divided and this application filed September 5, 1929. Serial No. 390,490.

This invention relates to fountain cuspidors, with particular reference to cuspidors used in the professions, such as dentistry and medicine.

5 The subject matter disclosed and claimed herein constitutes a division of an application for fountain cuspidors, filed Nov. 30, 1926, Ser. No. 151,736, patented April 15, 1930, No. 1,754,757.

10 In the application above identified there was disclosed a fountain cuspidor of novel construction and possessed of numerous advantages over the prior art. In its simplified and preferred form the cuspidor comprised a unitary drainage and distributing head through which all of the water and waste of the cuspidor passed. A bowl was mounted on the upper end of the head, while the lower portion of the head engaged with 15 a support housing drainage and water supply passages or conduits, while a branch extended laterally and upwardly from the head carrying a tumbler bowl and its associated supply and drainage passages.

20 The objects of the present invention are; to improve the construction of drinking glass supply mechanism; to provide and improve drinking glass bowls; to provide in a cuspidor or the like, valve mechanism operable through movement or pressure of the glass; to provide a unitary tumbler support and nozzle; to provide a drinking glass bowl and tumbler support of improved construction 25 wherein incidental leakage through the valve mechanism is unobtrusively carried off, and many other objects and advantages as will become more apparent as the description proceeds.

25 In the accompanying drawing:

Fig. 1 represents a vertical section through a drinking glass bowl of modified construction, and through an associated drinking-glass supply valve,

30 Fig. 2 represents a vertical section through a modification of the same,

Fig. 3 represents a vertical section through a further modification of the same, and

35 Fig. 4 represents a fragmentary side elevation of the device shown in Fig. 3, showing

in dotted and full lines the positions to which the valve actuating device is movable.

Although the invention is primarily adapted to be supported upon cuspidors or the like, yet it is capable of general application.

Upon the upper end of the tubular pedestal or arm or the like, D', a drinking tumbler bowl 197 is mounted having a relatively large drainage outlet 198 communicating with the branch or pedestal D'. The foregoing is 40 common to the several forms disclosed.

In Fig. 1, the water supply pipe 200 has a spring engaging web 201, a valve seat 202, and a guiding opening 203. A vertically movable unitary, (preferably) tumbler support and nozzle 204 terminates at its lower end in the stem of a valve 205, slidably mounted in the guide 203, and normally seated by a spring 206 engaged between the valve and the web 201, the unitary element includes a ported passage 207 through which water passes into the nozzle when the valve is unseated, as by downward pressure from the tumbler. In this and the other modifications the water pipes may be supported in any desired manner, (not shown).

In Fig. 2, the water pipe 208 has a valve seat 210, and a threaded guide 211, through which the ported valve 212 is threaded carrying at its upper end the tumbler supply 70 nozzle and support 213, and arranged for seating or unseating upon rotation of the valve by proper rotation of the tumbler through frictional engagement with the support or by rotating the nozzle. The water 75 passes through passage 214.

In Fig. 3, the water pipe 215 terminates in a valve chamber 216, having a seat 217, and closed by the shouldered sleeve or guide 218. A combined tumbler support and nozzle 220, 80 having cross-piece 221 on the nozzle, terminates in an extension having a passage 225 slidably mounted in the sleeve, and carries a valve head 223 normally held against the seat by a spring 226 engaged between the rear face of the valve head and the shoulder of sleeve 218. Upward thrust of the tumbler against the cross-piece unseats the valve, admits water to the valve chamber, and through port 224 in the sleeve to the passage 225. 85

Various modifications of these valves may occur to those skilled in the art, and it is to be noted that due to the formation and location of the parts, any slight incidental leakage that occurs during the use of any of the valves shown in Figs. 1 to 4, inclusive, will be carried off unobtrusively through the drainage passage of the branch D'.

The advantages of the invention will be apparent.

I claim as my invention:

1. In a cuspidor, a drainage member, a bowl mounted thereon, the member and bowl having communicating drainage passages, a water supply pipe housed in the drainage passage, a unitary tumbler support and nozzle arranged for movement under direct actuation by a tumbler, a valve normally closing the water supply pipe and operable by such actuation to admit water to the nozzle.

2. In a cuspidor, the combination with a water supply pipe, a support in which said pipe is housed, a bowl mounted on the support, the bowl and support having drainage passages in communication, a valve chamber mounted on the pipe in the drainage passage, a valve in the chamber normally closing said pipe and axially movable for unseating to admit water through the pipe, a tumbler support and associated nozzle connected to the valve and responsive to actuation from a tumbler to unseat the valve and admit water to said nozzle.

3. In a cuspidor, a substantially cylindrical hollow support, a concentric ported bowl on the support, a water supply pipe concentrically disposed in the support and having a valve seat and a valve chamber, an axially movable valve normally seated on said valve seat and having a passage therein, a tumbler support mounted in the bowl and connected to the valve and concealing the valve chamber, a nozzle operatively mounted relative to the tumbler support in the bowl and having a communicating passage with the passage in the valve, the admission of water to the nozzle passage being responsive to axial movement of the valve under the impulse of the tumbler, any leakage from the valve chamber being unobtrusively discharged into the hollow support beneath the tumbler support.

4. In a cuspidor, a water supply pipe, a valve element having a stem portion having a passage therethrough and normally closing the water supply pipe, a nozzle in communication with the stem portion of said valve and having a portion laterally offset relative to the axis of said stem portion, a tumbler support mounted on the valve element substantially concentric with the axis of the stem portion, the offset portion of the nozzle located beyond one side of the tumbler support and comprising a portion in substantial

parallelism with the axis of said nozzle and having a mouth disposed vertically above the bowl, said nozzle, valve element and bowl comprising a unit arranged for movement under directing actuation by a tumbler to operate the valve to control the passage of water through the nozzle.

In testimony whereof, I affix my signature.

CLARENCE W. MOORE.
